UNITED STATES PATENT OFFICE.

PAUL MUDROCH, OF PITTSBURGH, PENNSYLVANIA.

RAILWAY-RAIL JOINT.

1,097,347.

Specification of Letters Patent. Patented May 19, 1914.

Application filed January 17, 1914. Serial No. 312,706.

To all whom it may concern:

Be it known that I, PAUL MUDROCH, a citizen of the United States, and residing at Pittsburgh, in the county of Allegheny and State of Pennsylvania, have invented certain new and useful Improvements in Railway-Rail Joints, of which the following is a specification.

This invention relates to railway rail joints.

The object of the invention is to provide a structure of this character which shall be thoroughly effective in holding the meeting ends of two rails in positive alinement, and in which loosening of the fastening means of the fish plate will be reduced to a minimum whereby accidents resulting therefrom will be eliminated.

Another object of the invention is to provide a structure in which the necessity for bolt holes, usually six of them, in the ends of the rails is eliminated.

With the above and other objects in view as will appear as the nature of the invention is better understood, the same consists in the novel construction and combination of parts of a railway rail joint, as will be hereinafter fully described and claimed.

In the accompanying drawing forming a part of this specification and in which like characters of reference indicate corresponding parts: Figure 1 is a view in side elevation of a railway rail joint constructed in accordance with the present invention. Fig. 2 is an inverted plan view of the joint. Fig. 3 is a transverse sectional view taken on the line 3—3, Fig. 1. Fig. 4 is a perspective view of one of the fish plates. Fig. 5 is a perspective view of the bolt and clamp utilized in holding the fish plates assembled on the rails. Fig. 6 is a view in side elevation like Fig. 1, of a slightly modified form of construction. Fig. 7 is an inverted plan view of the form of construction shown in Fig. 6. Fig. 8 is a transverse sectional view taken on the line 8—8 of Fig. 6. Fig. 9 is a view in perspective of one of the fish plates of the construction shown in Figs. 6 to 8. Fig. 10 is a perspective view of the bolt and clamp utilized in holding the fish plates of the construction shown in Figs. 6 to 9 assembled on the rails, and, Fig. 11 is a transverse vertical sectional view of a still further modified form of fish plate.

Referring to the drawings and to Figs.

1-5 thereof, T designates the treads of two rails which may be of the usual or any preferred construction, W, the web thereof, and B, the base. The opposed ends of the two rails as usual, are supported by sleepers S which may be disposed as shown, or otherwise.

The feature of the present invention resides in a novel form of fish plate, the construction of which is such as to insure that the meeting ends of the rails will be maintained in absolute alinement, and that accidental disconnection of the fish plates from their intended position will be eliminated and that it will not be necessary to drill holes for bolts in the ends of the rails, as is done in the present system of railway rail joints. In order to secure this result, each fish plate is provided with a shoulder 1 to rest against the under side of the tread with a longitudinally channeled web 2 to bear against the like portion of the rail, with a base 3 to rest upon the like portion of the rail, with a flange 4 to overhang the edge of the base of the rail, and with an intermediate seat 5, forming a continuation of the flange 4 and arranged to embrace one-half of the base and to extend beneath the same, the like portions of the rail on its opposite side being similarly guarded by a fish plate, a counterpart of the one just described. The seats 5 rest upon a sleeper S² so that the depression of the rails at their meeting points is obviated and unnecessary strain upon the fish plates is obviated. The fish plates are held assembled with the rails primarily by spikes 6 which operate in the usual manner of such attachments.

As shown in Fig. 2, the opposed faces of the two seat members are provided with oppositely-disposed interlocking saw toothed shoulders 7 which are designed to prevent lateral displacement of the fish plates and the latter are firmly held assembled by bolts 8. The manner of combining these bolts with the fish plates to guard, as far as possible, against their detachment from vibrations or other causes, from the plates, consists in providing one end of each bolt with a clamp 9 having a toe 10 that is designed to overlie the edge of the rail base where the latter extends through a slot formed in the base 11 of a recess 12 provided in the outer face of the web 2, a removable clamp 12 being disposed upon the end of the bolt

opposite that carrying the clamp 9 and being held assembled therewith by a nut 13 serving to complete the clamping means. It is designed that the two clamps shall be 5 housed within the recesses 12' formed in the outer faces of the bosses 2' of the webs 2, as shown in Fig. 3, so that any lateral turning of the clamps will be positively precluded. Said bolts may be put in, *i. e.*, their heads 10 used, from either side of rail. The shanks 8 of the bolts pass beneath the bases of the rails, thereby rendering unnecessary any change or alteration of the rail to adapt it to receive the bolt. As a further means of 15 obtaining a positive assemblage of the fish plates with the rails, a bolt 14 is employed which passes through the fish plates, the opposed ends of the rails being provided with seats 14' to receive the bolt which is firmly 20 locked in position by a nut 15.

In the form of the invention shown in Figs. 6 to 10, the same principle of interlock of the fish plates is involved, the rail seat 5^a of each fish plate however, extending 25 throughout the length of such fish plate, and the integral clamp or head 9^a on bolt 8^a is flat faced and abuts against the edge of the rail base as shown in Fig. 8 instead of being provided with a nose to engage over 30 the rail base, as in the construction shown in Fig. 3. In other respects the construction of the parts being the same, like numerals of reference have been applied thereto.

35 In the form of the invention shown in Fig. 11, the fish plates 16 have at their lower edges, flanges 17 that engage around the outer edges of the base or the rail, the plates being held in position relative to the rail by 40 means of a clamp 18, the ends of which are bent around the flanges 17 of the fish plates, and project a sufficient distance toward the web of the rail to insure the retention of the clamp in position. It will be noted that the 45 fastening means in all forms of the invention, namely, the bolts 8 in Figs. 1-5, the bolts 8^a in Figs. 6 to 10, and the clamp 18 in Fig. 11 pass beneath the rail base and embrace or engage with the fish plates on 50 a plane above the upper surface of the rail base. The bolts 8 and 8^a are shown as inserted from opposite sides of the rails. Obviously, they may be inserted from the same side if desired. In the construction shown 55 in Figs. 1 to 5, the nose 10 engaging over the rail base serves as an additional clamp to securely hold the parts.

While the improvements herein described are simple in character, they will be found

thoroughly efficient for the purposes de- 60 signed, and will co-act in the production of a thoroughly efficient and reliable form of railway rail joint.

What I claim as new is:—

1. A railway rail joint without the usual 65 holes in the ends of rails and without the bolts to engage in those holes, comprising two fish plates having extensions constituting rail seats to pass under the bases of the rails and to be interlocked and means for 70 securing the fish plates in locked relation relative to the rails and for preventing longitudinal movement of the fish plates and rails relative to each other.

2. A railway rail joint without the usual 75 holes and bolts in ends of rails, comprising two fish plates having extensions constituting rail seats to pass under the bases of the rails, the opposed faces of the seats being provided with angularly-disposed shoulders 80 arranged to be interlocked by longitudinal movement of one seat relative to the other, and means for securing the fish plates in 85 locked relation relative to the rails and for preventing longitudinal movement of the fish plates and rails with regard to each other.

3. A railway rail joint without the usual 90 holes and bolts in the ends of rails, comprising two fish plates having extensions 95 constituting rail seats to pass under the base of the rails and to be interlocked, each of the seats being provided on its outer side with key-hole-shaped recesses, and bolts passing through the seats and having special 100 heads on one end engaging in the recesses in the seat of one fish plate, and keepers on the opposite ends of the bolts engaging in the recesses in the seat of the other fish plate.

4. A railway rail joint without the usual 105 holes and bolts in the ends of the rails, comprising two fish plates having extensions constituting rail seats to pass under the base of the rails and to be interlocked, each of the seats being provided on its outer side with key-hole-shaped recesses, and bolts with special heads passing through the seats and having keepers engaging the recesses, the bolts being disposed beneath the bases of 110 the rails.

In testimony whereof I affix my signature in presence of two witnesses.

PAUL MUDROCH.
